UNITED STATES PATENT OFFICE.

JOHN G. HODGSON, OF MAYWOOD, ILLINOIS, ASSIGNOR, BY MESNE ASSIGNMENTS, TO AMERICAN CAN COMPANY, OF JERSEY CITY, NEW JERSEY.

POWER-PRESS.

SPECIFICATION forming part of Letters Patent No. 681,023, dated August 20, 1901.

Application filed October 22, 1900. Serial No. 33,969. (No model.)

To all whom it may concern:

Be it known that I, JOHN G. HODGSON, a citizen of the United States, residing in Maywood, in the county of Cook and State of Illinois, have invented a new and useful Improvement in Power-Presses, of which the following is a specification.

This invention relates to improvements in power-presses.

10 It consists in the combination, with a driving-shaft of a power-press and a clutch by which the driving-pulley is connected with and disconnected from the shaft, of an automatic safety trip mechanism which automatically disconnects the power from the press after one complete revolution of its driving-shaft and prevents such disconnection before such complete revolution, although the clutch-treadle itself may in the meanwhile 15 be operated or moved through accident or carelessness of the operator.

It further consists in the novel construction of parts and devices and in the novel combinations of parts and devices herein shown 20 and described, and specified in the claims.

In the accompanying drawings, forming a part of this specification, Figure 1 is a side elevation of a power-press embodying or provided with my invention. Fig. 2 is a detail 25 front elevation, partly in vertical section. Fig. 3 is a perspective view of the segment-cam for automatically withdrawing the clutch-pin after one revolution. Fig. 4 is a perspective view of the clutch-pin. Fig. 5 is a perspective view of the spring-lock by which the clutch-pin is withdrawn, and Fig. 6 is a perspective view of the safety-trip.

In said drawings, A represents a power-press having the customary frame a, bed- 30 plates a', lower die a'', movable die or plunger a'', driving-shaft A', and power-pulley A'', loose on the shaft.

B is the clutch-pin, mounted in the power-pulley A'' and normally pushed outward by 40 a spring b, which causes the same to engage the recess b' in the clutch-collar B', which is secured fast to the driving-shaft A' of the press.

C is a movable lock mounted on the power-pulley A'', the same having, preferably, a sliding movement thereon in a radial direction

and which operates to hold the clutch-pin B in its retracted position by engagement of its upper end with the clutch-pin or with a projection b'' thereon, the said projection having, preferably, a notch b'', in which notch the upper end of the lock C may fit when the clutch-pin is withdrawn, while the projection b'' may ride on the upper end of the lock when the clutch-pin is pushed out by its spring b into engagement with the clutch-collar B'. The lock C has a spring C' to force it toward the clutch-pin as required. D is a segmental cam or block having an inclined or cam face d, which operates to automatically push back or withdraw the clutch-pin B when the power-pulley A'' completes a single revolution. When the clutch-pin is thus withdrawn, its projection b'' slips off the upper end of the lock C, and thus permits the lock C to slip 70 into the position to hold the clutch-pin retracted, as illustrated in Fig. 2. The segment-cam D has a face or edge d', which fits or projects over a lip or projection C'' on the lock C, so that by moving the segment-cam 75 downward the lock C may be retracted, and thus permit the clutch-pin B to again move outward or into engagement with the clutch-collar. For this purpose the segment-cam is preferably given a vertically-sliding move- 80 ment and is furnished with a stem or operating-rod D', reciprocating in suitable guides D'' on the frame, the same being normally pushed or held upward by a spring D'', which bears against a collar D', secured to the stem 85 D'. The stem D' is also furnished with a collar, hook, or projection d'' at its lower end, adapted to be engaged by the safety-trip F, which is interposed in the connection G G' between the clutch-treadle G'' and the segment-cam D or its operating-rod or stem D'. The connecting part G from the treadle is preferably a swinging arm or lever, and the safety-trip F is pivoted to it by a pin g, and the lever G is furnished with an arm g', be- 90 tween which and the safety-trip a spring g'' is interposed to push the safety-trip out into position for engagement with the collar, hook, or projection d'' on the stem D'. The safety-trip F is furnished with a rounded projection 95 or pin f, which is engaged by a lever H, having an antifriction-roller h at its upper end,

which is automatically engaged and operated by a cam H' on the driving-shaft A' of the press. The collar, hook, or projection d² on the operating-rod D' of the segment-cam D is provided with an inclined face or cam D⁵ to permit the same to move freely past the safety-trip F when the safety-trip is moved back into its uppermost position by the treadle-spring G⁸. The cam H' holds the safety-trip F retracted out of position for engagement with the collar or projection on the segment-cam operating rod D', except for a short part of the revolution of the shaft A'.

The operation is as follows: When the clutch-treadle is depressed, the parts being in the position illustrated in Figs. 1 and 2, the safety-trip is thus in position to cause the clutch-treadle to operate the segment-cam, and thereby retract the lock C. Said lock is retracted and the spring of the clutch-pin B pushes the clutch-pin outward into engagement with the clutch-collar B', thus causing the driving-shaft A' of the press to revolve until the power-pulley A² makes one complete revolution. No further movement of the clutch-treadle can have any effect upon the clutch-pin until the revolution is completed, because very shortly after the revolution begins the cam H' through the lever H, pivoted at h', retracts the safety-trip out of position for operation upon the segment-cam and holds the safety-trip in this retracted position until the revolution is completed. This retraction of the safety-trip permits the segment to be almost instantly restored to its normal position by its operating-spring, and when the revolution is completed the clutch-pin B is automatically withdrawn by its engagement with the segment-cam, and the instant the clutch-pin is thus withdrawn the lock C holds it in its retracted position until said lock is again withdrawn by operation of the clutch-treadle at the proper time—that is to say, when the revolution is completed. The safety-trip by reason of the cam H' prevents any movement of the clutch-treadle from having any effect excepting when the revolution is complete and the upper die or plunger of the press is open or withdrawn. When the power-press is stopped for examination or repairs, by simply hooking or tying back the safety-trip F all danger or possibility of the press being accidentally set in operation or connected with the power-pulley is absolutely avoided. The safety-trip F has a hook f² for this purpose.

It will be understood by those skilled in the art that the sheet metal or other material being operated upon by power-presses is ordinarily placed between the dies by the hand of the operator, and this safety-trip mechanism, which causes the driving-shaft of the press to always make just one complete revolution and prevents the press-shaft from being disconnected from the power-pulley before the downward and upward strokes of the upper die or plunger are completed and prevents the clutch

from being operated by the clutch-treadle except at the right time, while causing the press-shaft to be automatically unclutched from the power-pulley when the revolution is completed, is of very great convenience and importance in the practical operation of power-presses or other similar machines and adds materially to the safety of the persons operating the same, as well as preventing breakage, stoppage, or clogging of the mechanism. By this improvement the press is prevented from making more than one stroke or revolution at a time, no matter whether the operator works the foot-treadle slow or fast or even keeps the treadle depressed, and the operator is entirely freed from the necessity of watching the press and keeping time therewith in working the treadle, as has heretofore been the case with presses heretofore in use. In other words, by this improvement the press is always automatically stopped at the right point or time and cannot be again started except at the beginning of a new stroke. It absolutely prevents two revolutions of the crank-shaft of the press with one motion of the foot-treadle, which heretofore has been the chief danger to operators of power-presses.

I claim—

1. In a power-press, the combination with the driving-shaft and power-pulley, of a clutch-pin, a movable lock for holding the clutch-pin retracted, a movable cam segment or block to automatically withdraw the clutch-pin, a clutch treadle or lever, a connection between the same and said movable cam segment or block, a safety-trip in said connection, and a cam and lever for automatically retracting said safety-trip, substantially as specified.

2. The combination with a clutch-collar and spring clutch-pin, of a lock for holding the clutch-pin withdrawn, a movable cam segment or block to automatically withdraw the clutch-pin, mechanism for retracting said lock provided with an automatically - operated safety-trip, substantially as specified.

3. The combination with the clutch having a clutch-pin and its operating mechanism, including a movable lock for holding the clutch-pin retracted, a movable cam segment or block to automatically withdraw the clutch-pin, of an automatic safety-trip, substantially as specified.

4. The combination with clutch having a clutch-pin, of a movable lock for holding the clutch disengaged, a movable cam segment or block to automatically withdraw the clutch-pin, mechanism for operating said lock provided with a safety-trip, and automatic mechanism for operating and holding said safety-trip retracted, substantially as specified.

5. The combination with a clutch-collar and spring clutch-pin B, having projection b², of movable lock C, having projection C², cam segment or block D having operating stem or rod D', safety-trip F, lever H and cam H', substantially as specified.

6. The combination with a clutch-collar and

spring clutch-pin B, having projection b^2 , of
movable lock C, having projection C^2 , cam seg-
ment or block D having operating stem or rod
D', safety-trip F, lever H, cam H', connecting-
lever G, link G', and treadle or lever G², sub-
stantially as specified.

5 7. The combination with a clutch-collar and
spring clutch-pin B, having projection b^2 , of
movable lock C, having projection C^2 , cam seg-

ment or block D having operating stem or rod 10
D', safety-trip F, lever H, cam H', connecting-
lever G, link G', said connecting-lever G hav-
ing arm g' and spring g^2 , substantially as speci-
fied.

JOHN G. HODGSON.
